UNITED STATES PATENT OFFICE.

RICHARD BROMLEY, OF COLUMBUS, OHIO.

MINING-MACHINE.

SPECIFICATION forming part of Letters Patent No. 269,632, dated December 26, 1882.

Application filed June 8, 1882. (No model.)

To all whom it may concern:

Be it known that I, RICHARD BROMLEY, a citizen of the United States, residing at Columbus, in the county of Franklin and State of Ohio, have invented certain new and useful Improvements in Coal-Boring Machines, of which the following is a specification, reference being had therein to the accompanying drawings.

10 My invention relates to an improvement in machines for cutting coal; and it consists in the peculiar construction and arrangement of parts, whereby a simple, durable, and efficient coal-mining machine is produced, as will be more fully set forth hereinafter.

15 In the accompanying drawings, Figure 1 is a side-elevation of my machine. Fig. 2 is a top plan view, partly in section. Fig. 3 is a rear elevation, partly in section. Figs. 4 and 5 are 20 detailed views.

A represents a rectangular metallic frame, in which are journaled the parallel hollow shafts B, said shafts being considerably longer than the frame. At the forward end of the frame 25 the shafts are feathered to the sleeves a of the spur-wheels b, mounted therein, said spur-wheels meshing in with one another and serving to rotate the alternate shafts in an opposite direction, as will be readily understood.

30 The series of spur-wheels is inclosed in a tight box, A', as shown, so as to retain the lubricant and exclude the dirt.

At the forward and rear ends of the shafts B are journals in the transverse bars or heads 35 C and D, said bars having projecting ends, to which wires, ropes, or chains c are attached, said wires, ropes, or chains c being passed around the drums E, secured to the shaft F, journaled on the top and near the forward ends 40 of the frame A. By this construction the alternate shafts are not only adapted to be revolved in opposite directions, but they are capable of being advanced or withdrawn while in operation by means of the drums and ropes, 45 the mechanism for accomplishing this to be described farther on.

To the frontends of the shafts B are attached the cutter-heads G, each of the said cutter-heads having the flange g, the groove g', and 50 the opposite shoulders, g², projecting from the sleeve g³, and provided with holes g⁴, for the reception and retention of the cutting-tools. (Not shown.) As will be seen in Fig. 2, the alter-

nate cutter-heads are shorter than the others, their flanges g overlapping the flanges g' of the others and extending into the grooves g'.

Extending through the hollow shafts B are the spiral cleaning rods or conveyers H, which are provided with the pulleys h at their rear ends, around which and the pulleys h', mounted 60 on the rear bar, D, is passed the belt or chain h², in such a manner as to cause the alternate cleaning-rods to revolve in opposite directions, not only to each other, but to the shafts B, in which they rotate. To accomplish this the 65 belt is passed over one pulley and under the other throughout the series, the upper half of the belt being stretched straight from the pulley h'. Motion is imparted to one or more of the pulleys h', and through the belt to the series of cleaning-rods, by the spur wheel or 70 wheels h³, secured thereto and meshing in with a spur-wheel, b', with which one or more of the shafts B is or are provided, as shown in Fig. 3. By means of this construction the coal, as it is 75 cut by the cutter, is conveyed rapidly through the revolving shafts B by the reversed rotating cleaning-rods H revolving within them, thus greatly reducing the liability of the shafts to choke with particles of coal or fire-clay, this 80 being a feature of very great importance in the practical working of the machine, as will be readily understood.

The construction of the mechanism for advancing and withdrawing the cutting-heads is 85 as follows: Rigidly secured to the shaft F is the pinion f, meshing in with the spur-wheel I, mounted upon the frame A. This spur-wheel I is provided with a pinion, i, which is rotated by the rack-bar k', which is a forward extension 90 of the piston-rod K, which reciprocates in a cylinder, L, secured to the rear of the frame A. This cylinder L is provided with the inlet and outlet ports ll, for admitting and discharging water or oil when used as a hydraulic ram, 95 or with steam, compressed air, gas, or vapor, as preferred, and is provided with a safety-valve, l', admitting of easy adjustment to the pressure required to feed suitably to the material to be cut without undue strain upon the 100 machine, thus regulating the penetration of the cutters to the highest speed consistent with safety against breakage, the advantage being that the speed of the feed is adjusted to the hardness of the material to be cut, and not in 105 a fixed ratio to the revolutions of the cutters,

as now practiced, this being a great improvement, as will be readily understood.

A means of operating the cutters is shown in dotted lines, Fig. 1 of the drawings, and in which cylinders are arranged upon the plate A, the connecting-rods of which turn a worm-wheel, shaft, and gear-wheel, which meshes with the gear-wheel on one of the cutter-shafts.

Having fully set forth my invention, I claim—

10 1. The hollow shafts B, provided with the cutters G, and the cleaning-rods H, the alternate shafts being adapted to be revolved in opposite directions, and the cleaning-rods within them being revolved in opposite directions to the shafts in which they work, in combination with suitable mechanism for operating them, substantially as shown and described.

15 2. The hollow shafts B, provided with the rotating heads G, the transverse heads C D, the

shafts being feathered to the spur-wheels b and 20 rotated in opposite directions thereby, in combination with the spiral cleaning-rods H, adapted to revolve in opposite directions to the shafts in which they rotate, and the mechanism for operating the said cleaning-rods, as set 25 forth.

3. The cylinder L, provided with the adjustable safety-valve l' and the piston K, the piston being connected by suitable mechanism to the cutting-shafts B, and adapted to advance 30 and withdraw them, substantially as and for the purposes set forth.

In testimony whereof I affix my signature in presence of two witnesses.

RICHARD BROMLEY.
